CLAIM

The ornamental design for a pouch, as shown and described.

DESCRIPTION

FIG. 1 is a front perspective view of a pouch in unfolded configuration showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view wherein the pouch in a first folded configuration; and,
FIG. 10 is another perspective view wherein the pouch in a second folded configuration.
The broken lines in the drawings depict portions of the pouch that form no part of the claimed design.
